UNITED STATES PATENT OFFICE

CHARLES E. PUTMAN, OF SEATTLE, WASHINGTON

MACHINE FOR FORMING IMITATION SHAKES

Application filed September 3, 1927. Serial No. 217,511.

This invention relates generally to the shingle maker's art, and particularly to a machine for forming grooves in the weather portion of sawed shingles for the purpose of imitating split shakes.

The first object of this invention is to provide a machine for grooving the weather portion of sawed shingles in irregular waves for the purpose of closely resembling a split shake without the accompanying objections of airways being formed between the shingles when laid for the purpose of securing greater warmth and to the exclusion of insects.

The second object is to provide a machine which will not only groove the sawed surface of a shingle in irregular ways but is so constructed that no two consecutive shingles will be exactly similar in appearance, thereby de-

parting from the common objection to artificially created objects or appearances.

The third object is to produce a shingle grooving machine which can be set to groove a shingle a fixed distance from its tip and butt end independently of any qualities in the shingle thicknesses.

The fourth object is to produce a shingle grooving machine which will groove only a portion of the weather side of the shingle and to a uniform depth throughout the entire length of such grooving instead of gradually running out.

The fifth object is to so construct the machine that each shingle passing through the machine is automatically branded with the desired marking.

These, and other objects, will become more apparent from the specification following as illustrated in the accompanying drawings, in

which:

Figure 1 is a plan of the entire machine. Figure 2 is a vertical transverse section taken through the machine along the line 2-2 in Figure 4. Figure 3 is an enlarged fragmentary perspective view of a cutter blade. Figure 4 is a side elevation of the machine with a portion of its structure broken away to disclose the shingle passing through the machine. Figure 5 is a transverse section

50 through the lateral wave cam shafts show-

ing the two cams in position for the straight groove. Figure 6 is similar to Figure 5 but showing the cams in a position to produce two distinct waves in one shingle. Figure 7 is a perspective view of a processed shingle a portion of whose weather side is made to resemble a split shake.

Similar numbers of reference refer to similar parts throughout the several views.

Referring in detail to the drawings, the machine itself consists of horizontal and longitudinal frame members 10 and 11 which are joined by the cross ties 12. Between the members 10 and 11 are the upright standards 13 across whose upper end is secured the horizontal tie 14 between which and the member 11 is secured the short upright 15. End legs 16 unite the members 10 and 11 to the base 17.

Mounted across a pair of members 11 is a shaft 18 whose ends are supported in the bearings 19. On the shaft 18 is mounted a pair of sprocket wheels 20 and also the legs 21 of a hinged table 22 having a cut-out portion 23 formed near its mid section between the standards 13.

The opposite end of the table 22 is provided with the legs 24 in which journals a shaft 25 on which are secured the table raising cams 26 which ride on the rollers 27, which are mounted on the bearings 28 on the members 10. On the shaft 25 are also mounted the sprocket wheels 29 which are in line with the sprocket wheels 20 and the chains 30 pass around the sprocket wheels 20 and 29, as well as the sprocket wheels 31 which are mounted on the shaft 32 which journals in the bearings 33 on the legs 16.

Between the upright standards 13 are secured the horizontal brackets 34 on which are mounted the bearings 35 for the shaft 36 of the cutter head 37, whose blades 38 are provided with the irregularly grooved teeth 39 adapted to form a cross section in the surface of the shingle similar to that shown in the surface 40 of the shingle 41 whose surface 42 near its tip remains untouched as it passes through the machine.

The shaft 36 of the cutter head 37 is directly below the opening 23 in the table 22, and

the teeth 39 of the blades 38 project slightly above the surface of the table 22 when the cam 26 does not have its lobe 43 contacting with the roller 27.

5 Across the chains 30 are secured the pusher bars 44 which engage the butt 45 of the shingle 41 and feed it through the machine. Above the table 22, and along opposite edges of the opening 23, are the presser rollers 46 and 47 which are mounted on the arms 48 and 49 which, in turn, are hinged on the pivots 50 in the uprights 13 and 15. Springs 51 on the bolts 52 are used to urge the rollers 46 and 47 downwardly. The cross ties 53 support the upper ends of the springs 51.

10 On the shaft 36 is placed a pulley 54 around which passes the drive belt 55 from any suitable source of power. On the shaft 36 is placed a smaller pulley 56 whose belt 57 passes around the larger pulley 58 on the first counter shaft 59 whose pinion 60 meshes with the gear 61 on the second counter shaft 62. On the second counter shaft 62 is also mounted a gear 63 which meshes with the gear 64 15 on the branding roll shaft 65 which journals in the bearings 66 and carries the branding roll 67. The branding roll 67 is not a complete cylinder but a segment which permits the table 22 to be raised when the tip 42 of the shingle 41 is passing the cutter blades 38.

20 Meshing with the gear 61 is a gear 68 which drives the first lateral wave cam shaft 69 on whose outer end is secured the first lateral wave cam 70. The shaft 69 journals in the bearings 71. On the shaft 69 is secured a speed-changing gear 72 which meshes with a second speed-changing gear 73 on the stud 74. On the stud 74 and secured to the gear 73 is a third speed-changing gear 75 which 25 meshes with a fourth speed-changing gear 76 formed on the end of the sleeve 77 which journals on the shaft 69 and has secured to its outer end a cam 78, which is just inside of the cam 70.

30 A bell crank lever 79 has one of its arms 80 extending across both of the cams 70 and 78 and is urged toward them by the spring 81. The opposite end 82 of the bell crank lever 79 is forked to engage the groove 83 in the cutter head 37.

35 This arrangement of gears causes the cams 70 and 78 to be driven at slightly different speeds, which results in a constantly changing reciprocating motion being supplied to the cutter shaft 36, and since the shingle 41 is moving as it passes the cutter blades 38, it will, for example, be either grooved with a plurality of straight grooves approximately parallel to the sides of the shingle (if the cams 40 are in the position shown in Figure 5) or will be given one or two waves in either direction and along any portion of the length of the groove, depending upon which intermediate position the cams assume, as, for example, as 45 shown in Figure 6.

On the shaft 25 is secured a sprocket wheel 84 whose chain 85 also passes around the sprocket wheel 86 on the shaft 62 which supplies the movement for the chain 30.

The operation of the machine is as follows: 70 The operator places the shingle on the table with its tip foremost so that one of the pusher bars 44 will engage the butt 45 of the shingle 41. The constantly moving bar 44 now pushes the shingle tip 42 foremost under the rollers 47 and 46. At the instant the tip 42 is above the cutter, which is the moment it is not desired to process the shingle owing to the extreme thinness of such tips and the desirability of the close laying of the shingles 75 on the roof or wall, the lobe 43 is caused to rest upon the roller 27, which raises the table 22, and with it the shingle 41 clear of the cutter blades 38. However, as the tip 42 passes the cutter the lobe 43 drops off of the roller 27 and allows the shingle 41 to abruptly come in contact with the revolving cutter blades 38 instantly starting the fluting process. This is especially desirable, owing to the fact that the flutes are not uniform but extend in shallow waves across the shingle, each of the waves being itself fluted with rather fine 80 grooves, as can be seen in Figure 7.

85 It will be noted that, regardless of the thickness of the shingle 41, the rollers 46 and 47 will yield to accommodate themselves to such thickness.

90 As the shingle passes through the machine it finally comes in contact with the branding roll 67 and emerges from the machine fully 95 processed and branded.

95 As the next shingle passes through the machine the cams 70 and 78 have assumed a different relation to each other, which results in a different lateral wave being formed in the 100 surface of the shingle, so that no two consecutive shingles will be same in appearance when laid.

Naturally there will come a time when the 105 relation of the cams is again repeated, although such relationships will be far enough apart to remove the objectionable sameness common in imitation articles of manufacture.

110 While nature in its production of wood from which split shakes are made produces a 115 wavy effect, both laterally and, vertically, which might be likened to what is known as the hill and dale groove of a phonograph record, it can easily be seen that it is the lateral grooves which create the greatest impression 120 as to unevenness, and it is the vertical grooves, or the hill and dale grooves which are most difficult to fabricate, owing to the relative thinness of the shingle.

125 This machine has therefore been designed to reproduce the lateral wave since it lends itself to easy manufacture and creates the best impression when completed.

130 I am aware that many forms of grooving machines have been constructed in the past in

which various devices such as wash boards and other articles have been grooved along straight parallel lines; I therefore do not claim grooving machines broadly, but I do intend to cover all such forms and modifications thereof as fall fairly within the appended claims.

I claim:

1. A shingle fluting machine having, in combination, a fluted cutter head; a hinged table mounted above said cutter head provided with an opening through which said cutter can project when said table is lowered; a conveyor for moving shingles along said table across said opening; and means for supplying constantly changing lateral reciprocating movement to said cutter head, whereby the machine will produce a series of shingles each having a dissimilar arrangement of flutes.

2. A shingle fluting machine having a cutter adapted to form a plurality of irregular grooves in the weather side of a shingle, said cutter having two independent but cooperating means for reciprocating same laterally with relation to a shingle being grooved by said cutter while it is forming longitudinal grooves in same.

3. A shingle fluting machine consisting of a rotatable cutter having irregularly fluted cutting blades mounted thereon; a table hingedly mounted over said cutter having means for intermittently moving same away from said cutter for the purpose of rendering same momentarily inoperative; means for reciprocating said cutter head longitudinally on its axis with lateral relation to said table; and a conveyor for moving shingles across said table in a manner that the tip of said shingle is passing said cutter while same is not in contact with the shingle.

4. A shingle fluting machine having a rotatable fluted cutter; means for reciprocating said cutter longitudinally with its axis in a manner to produce curved flutes on a shingle passing said cutter; and means for automatically varying the degree and position of such curvatures, so that each shingle of a large series of shingles will be differently grooved whereby when they are placed together on a roof they will exhibit a pleasing degree of dissimilarity, imitating in that respect the expensive natural shake shingles.

5. A shingle fluting machine for processing the butt end of the weather side of a shingle consisting of a table on which the shingle can be moved; a fluted cutter mounted in close proximity to said table; means for varying the relation of said cutter and table to permit said cutter to extend through said table for the purpose of grooving a shingle passing thereover; means between said cutter and table for providing a lateral reciprocating movement between same, the time, degree and position of said movements constantly changing with succeeding shingles,

and branding rolls for marking each of said shingles as it emerges from said machine.

6. A shingle fluting machine having a frame; a fluted cutter mounted in said frame; a table hinged on said frame above said cutter having an opening therein through which the cutter can project when the table is lowered; a conveyor for moving shingles across the opening in said table; cams for raising said table away from said cutter as the tip of the shingle passes over said opening; yieldable pressure rolls on said table for holding said shingles against said table in their travel over same; and a branding roll on the opposite end of said table whereby a brand can be applied to the unprocessed side of a shingle as it passes said roll.

7. A shingle fluting machine having a cutter; means for reciprocating said cutter longitudinally with its axis consisting of a forked bell crank lever engaging the end of the cutter shaft; a pair of cams rotated at various speeds, each of said cams having lobes which can rock said lever; and dwells against which said bell crank lever can ride without operating same in a manner that the time, degree and position of curvature formed by said cutter is constantly changed.

8. A shingle fluting machine, the combination of a pair of shafts having means for driving same at unequal speeds; a cam on each shaft; a bell crank lever having one end which can engage either or both of said cams at the same time; a rotatable cutter having a slideable mounting and having its spindle connected to the second end of said bell crank lever; means for passing a shingle against said cutter in a manner to form grooves thereon across its entire weather side, except its tip portion; and means for branding the unprocessed side of said shingle as it passes through said machine.

9. In a surface treating device, a rotary shaft, means for revolving the shaft, a tool on said shaft, means for supporting a body the surface of which is to be treated, means for causing relative movement between the shaft and the supporting means so that the tool acts on said body, and means for moving the shaft axially as it revolves, said last mentioned means including two members moving at different rates of speed either capable alone of shifting the shaft along its axis, but both cooperating to so move the shaft, whereby the shaft is shifted in constantly changing fashion.

10. The device of claim 9 in which the tool is a rotary cutter, the body is a block of wood in shingle shape and the speeds of the two members are such that the shingles are each cut with a different groove so as to produce on a roof a pleasing non-uniformity.

11. The device of claim 9 in which the members are coaxial rotary cams.

12. In a shingle treating machine, a rotary

shaft, a cutter on said shaft, means for shifting the cutter laterally in constantly changing degree, and means for moving shingle blanks past the cutter and for intermittently moving the blank out of the path of the cutter without altering the lateral shifting of the cutter shaft.

13. The combination with a revolving cutter for grooving the face of a shingle, of a conveyor for moving a series of shingle blanks past the cutter, means for shifting the cutter laterally at constantly changing speed, the conveyor being driven at a speed not varying directly with the speed of the cutter so that the various shingles are grooved in non-uniform manner.

CHARLES E. PUTMAN.
